UNITED STATES PATENT OFFICE

HERBERT FROOD, OF BUXTON, ENGLAND.

BRAKE-BLOCK OR THE LIKE.

1,102,215.

Specification of Letters Patent. Patented June 30, 1914.

Original application filed September 4, 1913, Serial No. 788,458. Divided and this application filed April 18, 1914. Serial No. 833,002.

To all whom it may concern:

Be it known that I, HERBERT FROOD, a subject of the King of Great Britain and Ireland, and a resident of Buxton, in the county of Derby, England; have invented certain new and useful Improvements in Brake-Blocks or the like, of which the following is a specification.

With brake blocks, brake bands, flat or cone shaped friction clutch rings, or the like made of a thick woven fabric similar to driving belts and impregnated with hard cementitious material it is found that considerable and quickly repeated adjustment is necessary for some time after the band, block, ring or the like is first put in place and put to work. I have found that the necessity for making such adjustment arises, not from the wearing away of the fabric, but from its diminution in thickness resulting from the working pressure put upon it, which diminution progressively continues, until the fabric has been reduced to the least thickness it is capable of being reduced to under such pressure. When this state is arrived at the fabric composing the band or the like is only further reduced in thickness as a result of the frictional wear and attrition to which it is subjected, and as the wear is very small very little adjustment is required after the fabric can no longer be reduced in thickness by the working pressure put upon it.

This application constitutes a divisional application of application Serial No. 788,458, filed September 4, 1913, upon which Letters Patent No. 1,096,705 were granted May 12, 1914.

It has been suggested to subject such blocks, bands, rings or the like, or the strips from which they are cut, and before they are put in use, to a heavy pressure to consolidate them or render them more compact. But such pressure unless exerted under conditions which restrain the lateral and longitudinal flow of the fabric results not only in a reduction of thickness of the fabric but also in a lateral and longitudinal flow or extension of the fabric, so that the fabric after being pressed is longer and wider than it was originally. This lengthening and

widening of the fabric results in and from a stretching of the yarns from which the fabric is woven, and a deterioration of the strength of such yarns as a consequence of 55 the stretching thus given to them.

The object of my invention is to consolidate and render more compact such a fabric brake block or the like (hereinafter referred to as a brake block) by reducing it, by pressure, before it is put in use, to a thickness beyond which it cannot be further reduced merely by the pressure to which it is subjected under working conditions, and in carrying my invention into effect I subject my 60 brake block to the desired pressure in such a manner and under such conditions that although it is reduced to the desired thickness it is not increased either in width or in length, and the yarns of which it is composed are therefore not stretched and are 65 not deteriorated in strength and structure as a result of stretching. This is accomplished by placing the impregnated length of fabric which is to compose the ultimate 70 75 brake block in a die which closely surrounds the edges of the fabric and prevents it from flowing or stretching either longitudinally or laterally when pressure is applied to its face by a ram or the like and it is thereby reduced in thickness to the desired extent.

The condition obtaining in my improved woven and pressed fabric block is that its constituent yarns are compressed and are unstretched whereas in prior constructions 85 the constituent yarns although compressed are also stretched. The described die pressure is preferably exerted upon the brake block while it is in the curved form which it will occupy when in use. The block 90 should be warmed to soften the hard cementitious material contained within it, and the pressure be applied while the cementitious material is soft and comparatively non-resistant.

The accompanying drawings illustrate a die used for pressing a brake block to the condition described and also illustrate a block which has been so pressed.

Figure 1 is a plan view of a die in which 100 a brake block is pressed as described and in the curved form in which it will be used.

Fig. 2 shows such die in section and also the contained block with the ram by means of which the latter is pressed. Figs. 3 and 4 are cross sectional views of such block before and after pressing.

5 A represents the die with a recess *a* cut in its face which recess is just of the dimensions of the edge of the block which is to be pressed. The block B is cut to the 10 external edge dimensions of the recess *a* and is held in the die and bent to its curve and so as to lie at the bottom thereof while warm.

15 C is the ram which also fits the die and is pressed down to reduce the block in thickness. The walls of the die prevent the block B lengthening or widening. Figs. 3 and 4 show in cross section a fabric brake block B. In Fig. 3 before pressing, it is shown 20 as two inches wide and as three-quarters of an inch thick. In Fig. 4, after die pressing,

it is shown as still two inches wide but three-eighths of an inch thick.

What I claim is:

As a new article of manufacture, a solid 25 hard brake block formed of a thick woven fabric compressed in one direction to substantially the working pressure upon the block, while retaining its original dimensions in other directions, and a hard cementitious substance incorporated therewith, whereby the fibrous constituents of the block are retained in compressed and unstretched condition, and disintegration thereof is prevented.

30 In witness whereof I have hereunto set my hand in the presence of two subscribing witnesses.

35 HERBERT FROOD.
